CLAIM

The ornamental design for a heater, as shown and described.

DESCRIPTION

FIG. 1 is a perspective view of a heater, showing a first embodiment of my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view showing the heater in a alternative environment;

FIG. 8 is a perspective view showing the heater in another alternative environment;

FIG. 9 is a perspective view showing the heater in another alternative environment;

FIG. 10 is a perspective view showing the heater in another alternative environment; and,

FIG. 11 is perspective view showing the heater in another alternative environment.

Wherein, the broken lines are shown for illustrative purposes only and form no part of the claimed design.
